(57) **CLAIM**

The ornamental design for a patient airway tube with face shield and jaw position holder, as shown and described.

DESCRIPTION

FIG. 1 is a right-front isometric view of a patient airway tube with face shield and jaw position holder showing my new design;

FIG. 2 is a left-rear isometric view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.
